DUAL PHOTOTUBE X-RAY TIMER FOR
SELECTIVE EXPOSURE OF CHEST FILMSRussell H. Morgan and Paul C. Hodges, Chicago,
Ill., assignors to the United States of America
as represented by the Secretary of War

Application May 15, 1946, Serial No. 669,820

1 Claim. (Cl. 250—65)

1

This invention relates generally to a method and means for photographing the lungs in which exposure of the X-ray films is controlled by the translucency of the normal lung, and more particularly it is directed to an X-ray tuning mechanism by which the X-ray exposure of chest films may be controlled photoelectrically to produce films of optimum density of either the right lung or of the left lung or of the least radiopaque lung.

The device is desirable for use in chest radiography because under normal circumstances a normal lung is the least radiopaque lung and when a pathological condition is located on one side it is desirable that the normal side be properly exposed or at least control the density of the film so that the abnormal lung may produce on the film a density which may be compared with the density of the normal lung as appearing in the standard X-ray film.

One object of the invention is to provide a device for simultaneously photographing both lungs by X-ray and terminating the radiation on completion of the required exposure of the more translucent lung.

Another object of the invention is to provide an automatic photoelectric tuning mechanism whereby in chest radiography it is possible to control exposure by the radiation passing through the right lung or the left lung, or the more radiolucent of the two lungs, so that the pathological condition of the infected lung may be compared to the normal lung to determine the degree of infection.

Other objects and advantages will become apparent as the invention is more fully disclosed.

Referring to the accompanying drawing which illustrates diagrammatically the circuit and various elements of the invention the numeral 1 indicates an X-ray tube, 2 a grid, 3 the patient whose lungs are being photographed, 4 the photographic film and 5 and 6 fluorescent screens, adjacent the fluorescent screens are placed the two phototubes 11 and 17 which are connected respectively to two amplifier tubes 13 and 18 and two thyatron 16 and 21. The condenser 12 is connected between the control grid 13c of cathode 13d of the amplifier tube 13 through the grid bias resistor 14. In parallel with the condenser 12 is a normally-closed pair of contacts 25d of the relay 25. The plate 13a of the amplifier 13 is connected to the grid 16b of the thyatron 16 and is in series with the resistor 15 which in turn is connected to terminal 30. The cathode 16c of the thyatron 16 and one end of the resistor 14 are connected to terminal 29. Between terminals 29 and 30 is applied a 100-125 volt D. C. potential. The plate 16a of thyatron 16 is connected in series with the normally-open contact 25b of the relay 25 and the field coil of a D. C. relay 22 to terminal 30. The operation of the amplifier 13 is stabilized by maintaining the screen grid 13b of the amplifier 13 at constant potential by means of the voltage regulator tube 23 and the resistor 24.

2

10 The relay 22 possesses a pair of normally-closed contacts 22a which are in series with a pair of normally-open contacts 25a of the relay 25. These two sets of contacts are connected to terminals 31 and 32 and constitute a switch by means 15 of which power may be applied to the field coil of the contactor relay 33 of the X-ray machine and when power is applied to this field coil the contactor 34 is closed and the X-ray machine thereby energized. The field coil of the relay 25 is connected in series with the switch 26 through the terminals 31 and 32 to a 110-volt alternating current voltage supply. A high-voltage D. C. supply is applied between terminals 35 and 36. In series with terminal 36 is the variable resistor 37 and resistor 38 by which the dynodes of the phototube 11 receive the proper voltages for operation of this tube.

15 The anode 17a of the phototube 17 is connected to the condenser 40 and to the grid 18c of the amplifier 18. Condenser 40 is connected between the grid 18e and the cathode 18d of the amplifier 18 through the grid bias resistor 19. The plate 18a of the amplifier 18 is connected to the grid 21b of the thyatron 21 and in series with the resistor 20 which is connected to terminal 30. The cathode 21c of the thyatron 21 is connected to terminal 29 and the plate 21a is connected directly to the plate circuit of thyatron 16. The screen grid 18b of the amplifier 18 is also connected to the screen grid 13b of the amplifier 13 and this tube 18 is stabilized thereby in the same manner as tube 13. Phototube 17 obtains its operating voltage supply also through terminal 36, which is in series with variable resistor 39 and resistor 41 for supplying the potentials to the various dynodes of the phototube 17.

20 Also in the circuit is switch 42 which consists of a single-pole, three-position switch, shown in neutral position on contact 42b. The switch assembly includes the following contact points, terminal 42a which is connected to the plate 13a of the amplifier 13, 42b which is unconnected and 42c which is connected to the plate 18a of the amplifier 18. Terminals 43 and 44 may be connected to a voltage supply which may be de-

signed in a similar manner to similar voltage supplies described in previous patent applications compensating for the effect of phototimer operation which occurs when the voltage on the X-ray machine is changed. If this compensating mechanism is not desired, terminals 43 and 44 are connected together, as shown by the dotted line.

The method of operation of the invention is as follows: When switch 26 is closed, relay 25 is energized, causing the closure of terminals 25a and 25b and the opening of contacts 25c and 25d. When contact 25a is closed, the circuit between terminals 31 and 32 is completed and the contactor of the X-ray machine is energized and X-rays are thereby produced. Phototube 11 is placed behind a strip of fluorescent screen which fluoresces under the action of X-rays in a position immediately in the path of the projected X-ray beam which passes through the left chest of a patient standing in front of the device. Phototube 17 is placed behind a similar strip of fluorescent screen which is placed in a position directly in the projected beam of X-rays passing through the right chest. A cassette holding an X-ray film is placed between the subject under examination and the phototube-screen assemblies so that simultaneously with the action of the X-rays upon the phototube-screen assemblies X-rays are acting upon the film in the cassette. When the switch 42 is in position 42b, the X-rays passing through the subject under examination fall on the phototubes 11 and 17, causing phototube current to flow through both of these tubes, which collects on the respective condensers 12 and 40. The resulting potentials which develop across these condensers are applied to the respective amplifier tubes 13 and 18 and the amplified voltage applied to the grids of the respective thyratrons 16 and 21. As the voltage on the condensers 12 and 40 increases as the amount of collected charge accumulates, a potential is eventually reached, at which one or the other of the thyratrons will become conductive, causing current to flow through the relay 22 and opening the contact 22a of this relay. The circuit between terminals 31 and 32 is thereby broken, causing the deenergizing of the X-ray contactor and the termination of the X-ray exposure. The thyratron tube which will fire first, that is thyratron 16 or thyratron 21, in this process will be determined by which phototube receives the most light. The phototube which receives the most light from its corresponding fluorescent screen will charge up into the corresponding condenser more rapidly and will cause its thyratron tube to fire at the earlier time. Therefore, should pathology be present in one lung and not in the other and since pathology reduces the radiolucency of the lung, it, therefore, follows that the radiation passing through the normal lung will cause determination of the X-ray exposure.

If switch 42 is in position 42a, the amplified potential developed by the amplifier 13 is short-circuited and phototube 11 thereby has no effect on the length of the X-ray exposure; that is, X-ray exposure is entirely under the control of

the tube 17. Under this condition, the length of X-ray exposure is determined by the radiation passing through the right lung.

If switch 42 is in position 42c, the amplifier tube 18 therefore is short-circuited and the control of exposure is under the influence of phototube 11 and, accordingly, the length of exposure is determined by the radiation passing through the left chest. Thus, by means of switch 42 it is possible to obtain exposure control photoelectrically for X-ray exposures by means of the radiation passing through the right lung or left lung or the more radiolucent of the two lungs.

Having thus described our invention, what we claim as new and wish to secure by Letters Patent is:

An X-ray photographic apparatus for simultaneously producing adjacent comparative photographs of adjacently disposed anatomical structures upon a single photographic film, and during a single exposure period, the duration of which is dependent upon the translucency of the objects photographed, said means including a single X-ray tube, connected in a power circuit, an X-ray relay connected in a relay circuit and adapted to control said power circuit, electrically interrelated dual detection assemblies having identical functional characteristics, said assemblies having condenser thyratron circuits, a multiple switch relay including normally closed switches bridging each of said condensers, a normally open switch in said X-ray relay circuit for controlling said X-ray relay, and a normally open switch connected in the thyratron circuit, a direct circuit relay connected in said thyratron circuit, a normally closed switch in said X-ray relay circuit operated by said direct current relay and in series with the normally open switch in said X-ray relay circuit, said multiple switch relay operating to effect the opening of the condenser switches, the closing of the X-ray relay switch, and the closing of the direct current, thyratron circuit switch for the exposure period, and said direct current relay switch being adapted to open the X-ray relay circuit with the firing of the thyratron, and thereby terminate the propagation of X-rays.
